Inventor:

Andrew Carson,

United States Patent Office.

ANDREW CARSON, OF MEMPHIS, TENNESSEE.

Letters Patent No. 66,216, dated July 2, 1867.

IMPROVEMENT IN CLAPBOARD GAUGES.

The Schedule referred to in these Letters Patent and making part of the same

TO ALL WHOM IT MAY CONCERN:

Be it known that I, ANDREW CARSON, of Memphis, in the county of Shelby, and State of Tennessee, have invented a new and useful Improvement to be used by Mechanics in Weather-Boarding Houses; and I do hereby declare that the following is a full and complete description of the construction and operation of the same, reference being had to the accompanying drawings, making part of this specification, in which—

Figure 1 is a perspective view, and

Figure 2 is a detached section.

Like letters refer to like parts.

The object of my invention is to so construct an implement as to enable the mechanic to put weather-boarding on a house with greater facility and more accuracy than he could do in the usual way.

A represents a slotted plate with lugs, L, and having both edges bevelled, and inches, and fractions of inches, marked on the bevelled edges of the plate. B represents a slide, having the arm F jointed to it, and a set-screw, D, by which it is adjusted as it slides in the plate A. C represents the lug on the slide B, and to which the joint E of the arm F is attached. D represents a thumb-screw, the head of which slides in a groove in the back of the plate A, and serves to fasten the slide B in its place when properly adjusted on the plate A. E represents the joint in the heel of the arm F. F represents the arm of the implement upon which the board rests, and has a spur or dog, J, at its termination. G represents the fender on the upper end of the arm F. H represents that portion of arm F that supports the board. J represents a steel dog or point which is inserted into that part of arm F represented at H, and is fastened by a small screw in the side of the arm, as shown, but the dog or point can be cast in the arm. The edge of the dog or point is dressed with a longitudinal edge, which is in a vertical position or across the grain of the wood in order to prevent it from splitting the weather-boarding when driven in, which I find to be a great improvement upon the old plan of making the dog or point like a wedge, which, when placed near the end of the board, caused the board to split in driving the dog into the board. K, on the dotted line in the joint E, shows how much the joint is allowed to work, and as but little motion in the joint is needed but little is given. L represents stops on the back of the plate, which, when used, are to be placed against the lower edge of the weather-board. I represents the point on the lug of the joint E, which points to the inches on the bevelled edges of the plate A.

In using the above-described implement the mechanic will first slacken the thumb-screw in the slide, then move the slide until the point I points to the figure that corresponds with the width of that portion of the board that he wishes to expose to the weather; then tighten the screw D, and place the stops L, which are on the back of the plate A, against the lower edge of the weather-board, and with the heel of the hand drive the dog J into the board sufficiently deep to hold the gauge with the board upon it.

In the use of the above-described implement I have found it to be a very convenient tool in both speed and accuracy.

What I claim as my invention, is—

A clapboard gauge, composed of the graduated plate A, jointed and sliding-arm F, having projections G and H, with point J, and adjusted upon and held to plate A by means of the thumb-screw D, when all the parts are constructed to operate substantially as described and for the purposes set forth.
